Primary Examiner — Lauren D McVey(74) *Attorney, Agent, or Firm* — Hawaii Patent Services;
 Nathaniel K. Fedde; Kenton N. Fedde(57) **CLAIM**

The ornamental design for a monitor stand, as shown and described.

DESCRIPTION

FIG. 1 is a front, top perspective view of a monitor stand, showing my new design;

FIG. 2 is a rear, bottom perspective view thereof;

FIG. 3 is another front, top perspective thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a partial enlarged view taken from FIG. 1; and, FIG. 11 is a partial enlarged view taken from FIG. 6.

The dashed broken lines in the figures are for the purposes of illustrating portions of the monitor stand and form no part of the claimed design.

The dot-dash broken lines depict the bounds of the enlarged views and form no part of the claimed design.

1 Claim, 10 Drawing Sheets(56)
